CLAIM

Apr. 12, 2016 (KR) 30-2016-0017348

The ornamental design for a plunger for semiconductor
chip-testing probe, as shown and described.

(51) **LOC (11) Cl.** **10-04**

DESCRIPTION

(52) **U.S. Cl.**

FIG. 1 is a perspective view.

USPC **D10/80; D10/103**

FIG. 2 is a front view.

(58) **Field of Classification Search**

FIG. 3 is a back view.

USPC D10/80, 103; D14/437

FIG. 4 is a left side view.

CPC G01R 1/06; G01R 1/067; G01R 1/06705;

FIG. 5 is a right side view.

..... G01R 1/06711; G01R 1/06716; G01R

FIG. 6 is a top plan view; and,

FIG. 7 is a bottom plan view.

..... G01R 1/06738; G01R 1/06744; G01R

The present design relates to a plunger that is inserted into
a semiconductor chip-testing probe and has a conical-shaped
end. The material of the present design is metal.
